UNITED STATES PATENT OFFICE

2,622,770

CONNECTING CAP FOR AIR GUNS
AND THE LIKE

Glenn J. Penno, Denver, Colo., assignor to Tornado Manufacturing Company, Inc., Denver, Colo., a corporation of Colorado

Application February 6, 1948, Serial No. 6,795

7 Claims. (Cl. 222—464)

1

This invention relates to connecting caps for air guns and the like, and more particularly to a cap adapted to connect a sand blast air gun, paint spray gun or the like, with a container which contains material to be supplied to the air gun, for discharge therefrom. Such a gun may be constructed as disclosed in my copending application Serial No. 779,433, filed October 13, 1947, now Patent No. 2,487,366 of November 8, 1949, and entitled "Sand Blast Gun," while the material therefor may be any suitable abrasive sand or composition.

In sand blast guns, and also guns for spraying paint and the like, the material to be supplied to and discharged from the gun, such as an abrasive composition, paint, lacquer, varnish or the like, may be sucked up into the gun through a tube extending into the lower portion of the container. When the container is empty, or nearly empty, so that additional material will not be supplied readily through the tube to the gun, it is usually necessary for refilling to disconnect the gun and the container. The normal type of container previously in use is a bottle or jar having a screw thread at the upper end, while the gun may be provided with an integral or separate cap having a cooperating screw thread, such as shown in my copending application Serial No. 779,433, supra. However, unscrewing the container consumes an undue amount of time, and the screw threads also tend to become clogged with the material. When a connection which may be locked and unlocked relatively rapidly is utilized, such as pins extending from the container and adapted to cooperate with bayonet type slots in the cap, or vice versa, an adequate seal between the cap and the container is not provided, and the resultant loss of suction tends to become so great that the device becomes inoperative.

Among the objects of this invention are to provide a novel cap adapted to connect an air gun or the like, with a container adapted to receive material to be supplied to the air gun; to provide such a cap which may be provided with a quickly detachable connection with the container; to provide such a cap which insures an adequate sealing for the container, as to prevent loss of suction; to provide such a cap which is structurally fitted to accommodate a tube extending into the container; to provide such a cap which produces an adequate seal when a quick-acting connection of the pin and bayonet slot type is utilized; to provide such a cap which may take one or more different forms; and to

2

provide such a cap which is relatively easy to manufacture and assemble, and which will withstand rough handling and usage.

Other objects and the novel features of this invention will become apparent from the description which follows, taken in connection with the accompanying drawing, in which:

Fig. 1 is a three-dimensional view of a sand blast gun assembly, which includes a sand blast gun, a container, and a connecting cap constructed in accordance with this invention;

Fig. 2 is an enlarged side elevation of a portion of the sand blast gun and container, and the cap of this invention, certain parts being broken away and shown in vertical longitudinal section to illustrate more clearly the interior construction;

Fig. 3 is a transverse section taken along line 3—3 of Fig. 2; and

Fig. 4 is an enlarged fragmentary side elevation of the blocking connection between the cap and container.

As illustrated in Figs. 1 and 2, a sand blast gun G, which may be similar in construction to the sand blast gun of my copending application Serial No. 779,433, supra, is connected to a container or reservoir R by a cap C, constructed in accordance with this invention. The material in container R may comprise an abrasive composition or mixture, while air under suitable pressure may be supplied through a hose 18 to a passage 11 which extends through handle 12 into the body 13 of the gun, the flow of air through the passage being controlled by a valve actuated by a trigger 14. This air creates a suction effect by flow through a Venturi nozzle 15, and picks up the abrasive material supplied through a tube T from container R. The air carries the abrasive material through a discharge tube 16, the outer end of which is provided with a deflecting plate 17, adapted to intercept abrasive particles deflected back toward the operator. A hook 18 may be provided for supporting the gun from above during continued use at a specific location.

As illustrated in Fig. 2, the air flowing through nozzle 15 produces a jet smaller than discharge tube 16, and thereby creates a suction effect at an orifice 20 in the side of tube 16 just ahead of nozzle 15. The abrasive composition is sucked or pulled up into discharge tube 16 through orifice 20, from an abrasive passage 21 leading from a tube T, which extends into the lower portion of container R. The tube T may be attached to the body of the gun, as by a press fit

within a suitable hole in a downwardly extending threaded boss 22, by which the gun is attached to cap C, or the tube T may be threaded into the boss. Or, if desired, the tube T may be attached centrally to the cap C, below the threads by which the gun is attached to the cap.

The cap C, which is constructed in accordance with this invention, may comprise a body 24 having a rounded upper surface terminating centrally in a threaded hole adapted to receive boss 22 of gun G. The cap body 24 is provided with a circular, exterior depending flange 25, which fits over the neck 26 of container R, and a circular, interior depending flange 27, which forms a well for a coil spring 28, for a purpose described below. Exterior flange 25 may, as in Figs. 2 and 4, be provided with a pair of oppositely disposed bayonet slots 29, adapted to cooperate with pins 30 to attach the cap to the container R. Pins 30, of which there may be two, as shown, or any other desired number, are mounted on and extend laterally from neck 26 of container R.

The cap C includes sealing means, such as a circular disc 31 provided around the underside of its periphery with a washer or gasket 32, as in Figs. 2 and 3. The gasket 32 is formed of suitable material, such as natural or synthetic rubber, and is adapted to engage the circular upper edge of the neck 26 of container R. The sealing disc 31 is provided with a central hole 33 through which tube T extends, thereby permitting relative movement of the sealing disc 31 upwardly and downwardly on the tube T.

As will be evident, when the container R is locked and unlocked from cap C, the container must necessarily move into the cap, i. e., relatively axially, for the connecting pins 30 to clear the inside edges of the bayonet slots 29, but the sealing disc 31 is adapted to move with the container during such relative axial movement.

The sealing disc 31 is pressed downwardly against the upper edge of container R by coil spring 28, which surrounds tube T and the upper end of which may abut against the lower end of boss 22 of gun G. Spring 28 is received in the well formed by an inner flange 27 of cap body 24, as indicated previously. If desired, a suitable inwardly extending flange or boss may be provided, against which the upper end of spring 28 may abut. When the container R is unlocked and removed from cap C, as for refilling purposes, the sealing disc 31 is prevented from dropping out of the cap by suitable restraining means, such as a horseshoe washer 35 adapted to be inserted in an annular slot 36 formed in tube T. Preferably, the washer 35 is of a spring clip type which is spread during insertion in slot 36, and then closes slightly, so that the washer cannot be removed from the slot except by direct lateral pressure exerted thereon.

From the foregoing, it will be apparent that the connecting cap of this invention fulfills to a marked degree the requirements and objects hereinbefore set forth. The sealing disc 31, which is movable axially during locking and unlocking of the cap and container, insures that the upper end of the container will be adequately sealed. The sealing disc 31 is also disposed in a relatively protected position, being enclosed by the exterior flange 25 of the cap. None of the parts are at all complicated, and assembly of the cap is relatively simple. The gun G is preferably first attached to the cap, the tube T thus thereby extending through the cap. The coil spring 28 may then be dropped over the tube, followed by the

sealing disc 31. Pressure on the sealing disc will compress the spring 28, whereupon the washer 35 may be inserted in place. Also, if the gasket 32 should become worn, the sealing disc 31 is readily replaced. The pin and bayonet slot connection between the cap and container is readily locked and unlocked, the operator thereby saving much time during refilling.

Although a specific embodiment of this invention has been described and illustrated, and variations in certain of the parts described, it will be understood that numerous other variations may be utilized. For instance, relatively steep or fast acting screw threads may be substituted for the pin and bayonet slot connection between the cap and container; the cap may be utilized to connect a paint, varnish or similar liquid container with a spray gun operating on a suction principle, the sand blast gun herein described being illustrative only; the cap may be formed integrally with the body of the gun; resilient means other than a coil spring may be utilized for pressing the sealing disc against the upper edge of the container; and restraining means other than the washer shown may be utilized in restraining or preventing downward movement of the sealing disc beyond a predetermined extent.

It will, therefore, be understood that more than one embodiment of this invention may exist, and various changes may be made in such embodiments, without departing from the spirit and scope of this invention.

What is claimed is:

1. A cap adapted to connect an air gun or the like with a container for material to be supplied to said air gun, comprising a tube extending into said container; a cap body adapted to be connected to said air gun; an inter-locking connection between said cap body and said container, such connection producing relative axial movement between said cap body and container during locking and unlocking; a sealing disc mounted for movement along said tube axially thereof and disposed transversely thereto, said disc being adapted to engage the upper edge of said container; and a spring surrounding said tube above said disc and bearing downwardly thereagainst, for maintaining said sealing disc in engagement with said container edge while permitting axial movement of said disc during locking and unlocking.

2. A cap adapted to connect an air gun or the like with a container for material to be supplied to said air gun, comprising a tube extending into said container; a cap body adapted to be connected to said air gun and to substantially completely enclose the end of said container when connected thereto; an inter-locking connection between said cap body and said container, such connection producing relative axial movement between said cap body and container during locking and unlocking; a sealing disc mounted within said cap body for movement along said tube axially thereof and disposed transversely thereto, said disc being provided with a sealing washer adapted to engage the upper edge of said container; and a spring, surrounding said tube above said disc and bearing downwardly thereagainst, for maintaining said sealing washer in engagement with said container edge while permitting axial movement of said disc during locking and unlocking.

3. A cap adapted to connect an air gun or the like with a container for material to be supplied

to said air gun, comprising a tube extending into said container; a cap body adapted to be connected to said air gun; an inter-locking connection between said cap body and said container, such connection producing relative axial movement between said cap body and container during locking and unlocking; a sealing disc mounted for movement along said tube axially thereof and disposed transversely thereto, said disc being adapted to engage the upper edge of said container; a spring, surrounding said tube above said disc and bearing downwardly thereagainst, for maintaining said sealing disc in engagement with said container edge while permitting axial movement of said disc during locking and unlocking; and locking means associated with said tube for restraining downward movement of said disc upon removal of said container.

4. A cap adapted to connect an air gun or the like with a container for material to be supplied to said air gun, as defined in claim 3, wherein said locking means comprises a removable washer and said tube is provided with a slot to receive said washer.

5. A cap adapted to connect an air gun or the like with a container for material to be supplied to said air gun, comprising a tube extending into said container; a cap body adapted to be connected to said air gun, said gun having a boss and said cap body having an aperture adapted to receive said boss, said tube extending from said boss through said aperture; an inter-locking connection between said cap body and said container, such connection producing relative axial movement between said cap body and container during locking and unlocking; a sealing disc mounted for axial movement along said tube and disposed transversely thereto, said disc being adapted to engage the upper edge of said container; and a spring, surrounding said tube above said disc and bearing at its upper end against said boss within a well formed by said aperture and at its lower end against said disc, for maintaining said sealing disc in engagement with said container edge while permitting axial movement of said disc during locking and unlocking.

6. A cap adapted to connect an air gun or the like and a container adapted to receive material to be supplied to said air gun, comprising a tube extending into said container; a cap body adapted to be connected to said air gun, said cap body having an exterior, downwardly extending flange adapted to surround the upper end of said container, a central threaded aperture, and an interior flange extending downwardly from said aperture, said gun having a depending threaded boss adapted to be received in said aperture, and said tube extending down-

wardly from said boss and through said aperture; an inter-locking connection between said cap body and said container, such connection producing relative axial movement between said cap body and container during locking and unlocking, such connection including spaced bayonet-type slots in said exterior flange and correspondingly spaced pins extending from said container adjacent the upper end thereof; a sealing disc mounted for movement along said tube axially thereof and disposed transversely thereto, said disc having a central aperture through which said tube extends and a peripheral washer adapted to engage the upper edge of said container; a spring, surrounding said tube above said disc and received in a well formed by said interior flange, the upper end of said spring bearing against said boss and the lower end of said spring bearing against said disc, for maintaining said sealing washer in engagement with said container edge while permitting axial movement of said disc during locking and unlocking; and a horseshoe type locking washer for restraining further downward movement of said disc upon removal of said container, said tube having an annular slot adapted to receive said locking washer.

7. A cap adapted to connect an air gun or the like with a container for material to be supplied by suction to said air gun, comprising a tube extending into said container; a cap body adapted to be connected to said gun and to said container; and sealing means for said container and mounted on said cap body for axial movement relative to said tube and cap body, said sealing means being constructed so that said tube extends therethrough.
